CLAIM

The original and ornamental design for a combined wrist watch and toy vehicle, substantially as shown and described.

DESCRIPTION

FIG. 1 is a front elevational view of a combined wrist watch and toy vehicle showing my new design;
FIG. 2 is a top plan view thereof;
FIG. 3 is a bottom plan view thereof;
FIG. 4 is a rear elevational view thereof;
FIG. 5 is a left end elevational view thereof;
FIG. 6 is a right end elevational view thereof;
FIG. 7 is a top and left front perspective view of the toy vehicle watch with the holder/strap omitted for clarity of illustration;
FIG. 8 is a top perspective view of the holder/strap with the toy vehicle watch omitted for clarity of illustration;
FIG. 9 is a fragmentary top plan view of FIG. 8;
FIG. 10 is a bottom plan view of FIG. 7.

FIG. 9

FIG. 10
